APPARATUS FOR MECHANICAL AND HEAT TREATMENT OF METAL ARTICLES

Filed Aug. 21, 1930 2 Sheets-Sheet 2

UNITED STATES PATENT OFFICE

ROY C. INGERSOLL, OF GALESBURG, ILLINOIS, ASSIGNOR TO INGERSOLL STEEL AND DISC CO., A CORPORATION OF ILLINOIS

APPARATUS FOR MECHANICAL AND HEAT TREATMENT OF METAL ARTICLES

Application filed August 21, 1930. Serial No. 476,827.

My invention relates to the manufacture of steel clutch discs, harrow and plow discs and the like. When such articles are initially shaped and quenched, they are very brittle, and, when subsequently annealed to make them tough enough for use, they are susceptible to deformation during the heat-treating or annealing process.

It is an important object of my invention to provide a process for heat-treating clutch discs, harrow discs and the like to render such discs suited for hard use and rough handling in service.

It is also an important object of my invention to provide a process for heat-treating such thin metal articles as clutch discs and the like to render them capable of meeting hard service conditions without injury and to insure a uniform product with a minimum of spoilage during manufacture.

It is a further important object of my invention to provide apparatus whereby the above-mentioned process may be carried out.

In the drawings:

25 Figure 1 is a front view in elevation, with parts broken away, of a hydraulic press embodying the principles of my invention.

Figure 2 is a front view in elevation of a part of the press shown in Figure 1, with 30 parts broken away, and also showing details of control mechanism for the press.

Figure 3 is a sectional view through a part of Figure 2, showing the details of a valve for controlling the flow of fluid to the press.

35 As shown in the drawings:

The numeral 10 indicates generally a hydraulic press, which comprises, in common with presses of a similar character, a bed block 11 and a head block 11^a tied together by 40 tension rods 12.

45 Guide rods 13 extend between the head block and the bed block, and, slidably mounted on the guide rods are pairs of platens or die-receiving members 14. A fluid-pressed piston 16, suitably positioned in a cylinder 17 and arranged for connection to a fluid pressure system through a conduit 18, pushes the platens 14 upwardly.

For convenience in reading the drawings, 50 the platens have been given the letters A, B,

C, D, E and F to indicate the members of each pair and the order in which they rise. The platens 14 are limited in their downward travel by means of rods 19 which suitably engage lugs 20 on the platens 14 slidable on the rods.

Complementary dies 21 and 22 are shown mounted on the platens C and D to receive a dished harrow disc, and a pair of complementary dies 23 and 24 are shown mounted on the platens A and B to receive a flat clutch plate. The platens E and F are shown in the open position, ready for loading.

Steel clutch plates, harrow discs, or the like, are initially formed and quenched in any suitable manner. After quenching, they are usually so brittle that, should one fall on the floor, it will break as though made of thin glass. Such articles are usually annealed to render them fit for service, and, during the annealing process, they are susceptible of being readily deformed, so that the percentage of rejected plates because of deformation during previously known processes of treatment adapted to quantity production has been high.

In the practice of my invention, I place the steel plate, immediately after it has been quenched in an oil bath, in the dies of the hydraulic press. The platens 14 contain electrical heating units 25 suitably placed therein and connected to power supply lines through conductors 26, so that the temperature of the clutch plate, or similar article, may be raised to, and maintained at, the desired annealing temperature. The platen and the article housed therein are subjected to a moderate pressure for a certain length of time, during which the temperature of the article is being raised, and then subjected to a high pressure for a further period. The temperature of the dies is maintained at some predetermined value through the cooperation of a thermocouple 27 placed in one die or in both of the dies of each set with a conventional type of current regulator, indicated by the numeral 29, and to which it is connected by conductors 28. The regulator controls the flow of current from power supply lines 30 to the heater supply wires 26, in

any convenient and well understood manner.

While I have shown as a preferred embodiment of my invention a press employing hydraulic pressure it will be understood that 5 my process of mechanical and heat treatment may be carried out by other pressure producing means.

In carrying out my process of mechanical treatment and heat treatment, I apply a pressure of around 400 lbs. per square inch for 10 about a minute and a half and then supply a pressure of about 1,500 lbs. per square inch for three minutes, while the annealing temperature is maintained. This annealing temperature may vary between 400 and 1350 degrees depending upon the temper desired in the finished product. Employing the means described later for automatically operating the press, a fresh batch of plates is loaded 15 every six minutes, this period including the loading time.

Clutch plates and harrow discs that are exceedingly brittle when initially quenched are tough and ready for severe service after 20 the treatment in the press and subsequent cooling.

It is obvious that the annealing temperature and the duration of the mechanical treatment and heat treatment may be varied 25 to give the best results as the composition of the article to be treated is varied.

I have found that, when employing my method of mechanical treatment and heat treatment, the hydraulic press may be, advantageously arranged to automatically apply pressure in steps and to release the pressure for the unloading and loading of the platens.

In Figures 2 and 3, I have shown means 40 for obtaining automatic operation of the hydraulic press. A cam 47 is suitably driven to make one revolution in, say, six minutes. A valve-operating pivoted lever 48 having an end riding on the face of the cam 47 is 45 suitably connected to a valve spindle 49. A weight 50 on a pivoted lever 31 connected to lever 48 by a lost motion connection 32 is arranged to return the valve spindle 49 to its initial or upper position.

50 A valve housing 33 contains a cylindrical valve 34 slidable therein. The housing 33 is ported at 35 for connection to a high pressure system, at 36 for connection to a low pressure system, at 37 for connection to the conduit 18 leading to the piston cylinder 17, and at 38 to exhaust the fluid to a storage tank not shown.

The valve 34 is ported at 39 so that, at a certain position of the valve, the port 39 will 60 register with the port 36 to admit fluid at low pressure into the valve and thence by way of a slot 40 in the valve to the port 37.

When the valve 34 is in the position shown in Figure 3, it will be evident that it is in 65 the pressure-releasing or "exhaust" position

and that the fluid may flow from the cylinder 17 through the conduit 18, through the port 37, through the slot 40, and through a port 41 in the valve to emerge through the exhaust port 38.

70 It will also be evident that, as the spindle 49 is moved downwardly, the valve will consecutively apply low pressure and then apply high pressure; and that, on the upward stroke, it will consecutively cut off the high pressure, reduce the pressure to that of the low pressure system, and finally exhaust the fluid to the storage system. As the cam 27 revolves, it provides for a certain period of rest—no movement of the valve spindle in the exhaust position—so that the platens 14 may be unloaded and loaded.

75 It is obvious that the cam surfaces may be arranged to obtain any desired period of rest and any desired period of low and high pressure and steps in applying the pressure without departing from the spirit of my invention.

80 I am aware that many changes may be made and numerous details of construction may be varied through a wide range without departing from the principles of this invention, and I, therefore, do not purpose limiting the patent granted hereon otherwise than, necessitated by the prior art.

85 I claim:

1. The process of annealing pre-formed and hardened articles, such as steel harrow discs, which includes the steps of gradually raising the temperature of the article while it is subjected to a certain pressure and held confined to prevent deformation, and then increasing the pressure for a predetermined period of time while the annealing temperature is maintained.

100 105 2. Apparatus for simultaneously annealing and mechanically treating pre-formed and hardened articles, comprising means for supporting said articles thereon and confining them against deformation, means for heating said articles, pressure-applying means arranged to press said confining means to said articles, and means arranged to automatically control said pressure-applying means so that a certain pressure is maintained during a predetermined period of time, followed by a certain materially higher pressure for a predetermined period of time.

110 115 120 125 3. An apparatus for simultaneously annealing and mechanically treating pre-formed and hardened articles, comprising means for supporting said articles thereon and confining them against deformation, means for heating said articles, pressure-applying means including a piston arranged to press said means to said articles, and means arranged to control said pressure-applying means, said last-named control means including a valve casing having ports for communication with said piston and with a low pres-

sure fluid system and a high pressure fluid system, and a valve operable in said casing arranged to selectively connect said piston in fluid communication with said low and 5 high pressure systems.

4. An apparatus for mechanically treating pre-formed and hardened articles, comprising means for supporting said articles thereon and confining them against deformation, 10 pressure-applying means including a piston arranged to press said means to said articles, and means arranged to control said piston, said control means including a valve casing having ports for communication with a cylinder which receives said piston and with a low pressure fluid system and a high pressure fluid system, and a valve operable in said casing arranged to selectively connect said piston cylinder in fluid communication with said 15 low and high pressure systems.

5. Apparatus for simultaneously annealing and mechanically treating pre-formed and hardened metal articles, comprising die means to confine said articles, electrical heating means to heat said articles, and means for applying first a low and then a high pressure to press the dies on the articles while the articles are heated.

6. Apparatus for simultaneously annealing and mechanically treating pre-formed and hardened metal articles, comprising die means to confine said articles, electrical heating means to heat said dies, means in said dies in operative association with said electrical heating means to maintain a predetermined temperature of the dies, and means for applying pressure to press dies on the articles while they are heated and means for materially increasing said pressure.

7. Apparatus for simultaneously annealing and mechanically treating preformed metal articles which comprises a hydraulic press, dies to cooperate therewith, means for heating said dies and means whereby the 40 pressure exerted by said press is automatically increased.

8. Apparatus for simultaneously annealing and mechanically treating preformed metal articles which comprises a hydraulic press, dies to cooperate therewith, means for automatically maintaining said dies at a constant temperature and means whereby the pressure exerted by said press is automatically increased.

9. Apparatus for simultaneously annealing and mechanically treating preformed metal articles which comprises a hydraulic press, electrically heated dies to cooperate therewith, and means whereby the pressure exerted by said press is automatically increased.

10. Apparatus for simultaneously annealing and mechanically treating preformed metal articles which comprises a hydraulic press, electrically heated dies to cooperate 65

therewith, means for automatically maintaining said dies at a constant temperature and means whereby the pressure exerted by said press is automatically increased.

In testimony whereof I have hereunto subscribed my name at Chicago, Cook County, Illinois.

ROY C. INGERSOLL.
